UNITED STATES PATENT OFFICE.

JAMES S. HILLYER, OF DULUTH, MINNESOTA.

FURNACE.

1,356,147.

Specification of Letters Patent. Patented Oct. 19, 1920.

Application filed February 10, 1919. Serial No. 276,106.

To all whom it may concern:

Be it known that I, JAMES S. HILLYER, a citizen of the United States, residing at Duluth, in the county of St. Louis and State 5 of Minnesota, have invented certain new and useful Improvements in Furnaces, of which I do hereby declare the following to be a specification.

My invention relates to furnaces and has 10 for its object the provision of an improved furnace for heating purposes, which may be adapted to be used in connection either with a hot air or a hot water radiation system. It has for one of its objects the provision 15 of a core of non-combustible material adapted to extend into the fuel body whereby the fuel, such as coal, is excluded from the center of the furnace and confined to an annular space between said core and the inclosing wall. It has for a further object the 20 adaptation of such core to service as a container of air or water to be heated.

With these and other objects in view, it 25 consists of the structure, combinations and arrangements of parts hereinafter described and claimed.

In the drawings, Figure 1 is a central vertical section of one form of my said invention. Fig. 2 is a central vertical section 30 of a modified form of said invention. Fig. 3 is a top plan view of a part of a grate forming part of said invention. Fig. 4 is a front elevation of the form of said invention shown in Fig. 1.

35 In the drawings, 1 is a base section or ash chamber, of any suitable form or structure, upon which is mounted a fuel chamber, adapted to contain burning hard fuel, such as coal, which fuel chamber may, if desired, 40 embody a double wall 2 and 2^a (as in Fig. 2) with an intervening air or water space 2^b, or if preferred, said water space 2^b and wall 2^a may be omitted (as in Fig. 1). Extending over said fuel chamber and prefer- 45 ably supported thereby is a chamber 3 adapted to contain fluid, as air or water, which chamber is provided with a reduced central portion 3^b which extends into said fuel chamber and is adapted to form a core 50 in the fuel body whereby the fuel is ex- cluded from the center of said fuel cham- ber and confined to an annular space 4 formed between said core and the inclos- ing wall of said fuel chamber. Extending 55 through said chamber 3, is a series of flues 3^c of any suitable form or structure, prefer-

ably narrow crescent-shaped slots, through which the smoke and gases may pass upward from the fuel chamber to a smoke or gas combustion chamber 5 mounted upon 60 said chamber 3. If the water space 2^b is included in the structure, ports 2^c are provided leading from said space 2^b into the chamber 3. Upon said chamber 5 is mounted a hood, 5^a of any suitable structure, as is 65 well known to the art, with which hood the chimney connecting pipe 6 is engaged.

Within said base section is a spider 7 of any suitable structure, for supporting the grate, and preferably also for steadyng 70 the lower end of said core, the lower end of said core being preferably further reduced as at 3^d to form a wrist to engage said grate and preferably to engage said spider. Mounted upon any suitable support, as preferably upon said spider and journaled upon said wrist is a grate 8, 75 preferably comprising two semi-circular sections for convenience in assembling, which sections are adapted to be bolted together 80 in any suitable manner, as at 8^a. Said grate is approximately dish-shaped or concaved, with its periphery extending upward into said fuel chamber. The area of said grate below said annular fuel space 4 preferably 85 consists of a series of radial arms 8^b forked as at 8^c. Said grate below the body portion of said core preferably has broad seg- 90 mental openings 8^d formed therein through which the coarser cinders may fall into the ash pit. A grate-shaking lever 8^e may ex- 95 tend from the central ring of said grate to a point near the front of the base and op- posite to a horizontally disposed slot in said base through which an extension lever 95 (not shown) of any suitable structure may be directed and engaged with said shaking lever. Said slot may be covered by a door 8^f when said extension lever is not in use. A cold air or cold water supply pipe 9 100 extends into the lower end of said core at any suitable point, and if said water or air space 2^b is provided, a branch supply pipe 9^a is provided communicating with said space 2^b near its lower end. A hot water 105 or air exhaust, or circulation pipe 10 com- municating with the upper end of said fluid chamber at any suitable point and ex- tending in any suitable direction is adapted 110 to conduct the heated air or water from said chamber 3 to the radiation system (not shown). A suitable ash door 11 is pro-

vided in said base, and a suitable check draft door or clean-out door 12 is provided either in said hood or in the wall of said chamber 5. In view of the presence of said core, I prefer to have a plurality of stoking doors, so that the fuel may be conveniently and evenly distributed around said core. Said doors may be located at any convenient points but double doors at the front 10 as 13 and 14 affording a wide stoking passage are believed to be sufficient since a suitable poker can be inserted to rake the fuel behind the core to a common level with the fuel at the front and sides. If desired 15 a wide single door may be substituted for said double or plurality of doors.

One purpose of the core is to avoid waste of fuel at the center of the fuel chamber. By experimentation I have found that a 20 core composed of well-burned ashes will accomplish this purpose and that the live fuel between such core and the inclosing wall of the furnace as effectively heats the water in the outer and overhead chambers 25 as when the ash core is omitted, indicating that the excess heat from the center of the solid body of fire tends to waste in the chimney. A further indication of this is that without the ash core in the furnace 30 experimented with, the pipe connection between the chimney and the furnace is usually very warm or hot, while during the use of the ash core such connection is cool. Another purpose of the core in my furnace 35 is to bring into contact with the burning body of fuel an additional area of surface desired to be heated, whereby a larger proportion of the heat units are absorbed close to the points of their liberation and the 40 loss of heat in the chimney is reduced to a minimum.

Having now described my invention, what I claim is—

1. In a furnace, the combination of a 45 base unit, a fuel chamber unit, a grate adapted to approximately close the lower end of said fuel chamber, a unitary fluid heating chamber extending entirely across the upper end of said fuel chamber and

provided with a reduced portion extending 50 centrally into said fuel chamber to a point below the horizontal plane of the upper part of said grate, said fluid heating chamber having flues formed in the overhead portion thereof for the passage of products 55 of combustion from said fuel chamber, a smoke box unit extending over said fluid heating chamber and communicating with said flues, a fluid circulation pipe communicating with the lower end of said depending 60 portion of said fluid heating chamber and a fluid circulation pipe communicating with the overhead portion of said fluid heating chamber.

2. In a furnace, the combination of a 65 base unit, a fluid chamber unit mounted upon said base and having a centrally disposed fuel chamber extending therethrough, a grate adapted to approximately close the lower end of said fuel chamber, a second 70 fluid chamber unit extending entirely across said first fluid chamber unit and provided with a reduced central portion extending centrally into said fuel chamber to a point below the horizontal plane of the upper 75 part of said grate, said second fluid heating chamber having flues formed in the overhead portion thereof for the passage of products of combustion from said fuel chamber, said second fluid chamber having 80 passages formed in the overhead portion thereof adapted to communicate with the upper end of said first fluid chamber, a smoke box unit extending over said second fluid chamber and communicating with said 85 flues, a fluid circulation pipe communicating with the lower end of said first fluid chamber, a circulation pipe communicating with the lower end of the reduced portion of said second fluid chamber, and a circulation 90 pipe communicating with the overhead portion of said second fuel chamber.

In testimony whereof, I hereunto affix my signature, in presence of two witnesses.

JAMES S. HILLYER.
